Baldwin, N.Y. 11510

Filed Aug. 18, 1966, Ser. No. 3,518

Term of patent 14 years

(Cl. D54—12)

FIG. 1

FIG. 2

FIG. 3

FIG. 4

FIG. 1 is a front elevational view of a fork or similar article showing my new design;

FIG. 2 is a side elevational view thereof;

FIG. 3 is an end view thereof on an enlarged scale; and

FIG. 4 is a sectional view on an enlarged scale taken on line 4—4 of FIG. 1.

The dominant features of the design reside in the handle shown in full lines, the conventional tines being shown in broken lines. The rear elevation is substantially plain and unornamented.

I claim:

The ornamental design for a fork or similar article, substantially as shown and described.
